UNITED STATES PATENT OFFICE.

THEODORE FRUCHTMAN, OF NEW YORK, N. Y.

NECKTIE AND METHOD OF MAKING THE SAME.

1,379,256.

Specification of Letters Patent. Patented May 24, 1921.

Application filed April 27, 1920. Serial No. 376,945.

To all whom it may concern:

Be it known that I, THEODORE FRUCHTMAN, a citizen of the United States, residing at New York, in the county of New York and 5 State of New York, have invented certain new and useful Improvements in Neckties and Methods of Making the Same, of which the following is a specification.

My invention relates to a new and improved construction of necktie or cravat.

One of the objects of my invention is to produce a cravat or the like which shall slide through a turned-down collar of the well-known type, with a minimum of friction.

15 Another object of my invention is to produce a cravat which can be quickly and cheaply made.

Another object of my invention is to produce a cravat in which the filling material 20 is sewn throughout its entire length to the face fabric of the article so that it will not shift when in use and bunch up so as to lessen the life of the article.

Other objects of my invention will be disclosed in the following description and drawings which illustrate a preferred embodiment thereof.

Figure 1 is a rear view of my improved article.

30 Fig. 2 is a rear view of the facing or face fabric and the filling material.

Fig. 3 is a perspective view showing how the face fabric and filling illustrated in Fig. 2 are doubled over and sewed.

35 Fig. 4 is a section along the line 4-4 of Fig. 1.

Fig. 4^a is a detail section of the central part of Fig. 4.

Fig. 5 is a section along the line 5-5 of 40 Fig. 2.

Fig. 6 is a section along the line 6-6 of Fig. 3.

A piece of face fabric 1 is first cut out into suitable form, one of the shapes which 45 the blank of face fabric may assume being shown in Fig. 2.

A piece of filling material 2 is then sewed on to the rear of facing 1 by means of a line of stitching 3.

50 The filling material 2 is preferably made of a light thin material which is somewhat stiffer than the ordinary soft filling materials heretofore used.

The facing 1 and the filling 2 are now 55 doubled over along their median line so that the face of the fabric 1 is turned inside and

the two halves are now connected by a line of stitching 4 so as to form a sort of tube. The tube-like structure shown in Fig. 3 is now turned inside out so that the outside 60 of the facing 1 is now on the outside of the article.

The filling 2 now forms a sort of loose tubular structure inside of the facing 1, being connected to one half of the cravat by 65 the stitching 3 and being connected to both halves of the cravat by means of the stitching 4.

The stitching 3 and 4 can be done by means of the ordinary sewing machine.

As a result of the method of manufacture above mentioned, the filling is sewed to the facing along its entire length and along the edges thereof, while substantially all the rest of the filling is unsecured to the facing but 75 is in substantially fixed relation thereto.

I have shown a preferred embodiment of my invention but it is clear that numerous changes may be made in the method, and the construction of the article itself produced 80 by this new and improved method, without departing from the spirit of my invention.

It is preferable to have the filling material 2 of substantially the same contour as the adjacent part of the facing 1.

I claim:

1. A method of making a necktie or the like which consists in sewing the longitudinal edge of a piece of filling material to a longitudinal edge of the rear surface of a facing, then doubling over the said facing and filling material so that the facing is folded inside out, then stitching together the edges of the doubled-over facing and filling, and then turning the article thus made inside 90 out, a sufficient portion of the said filling being left unsecured to the said facing, so that the said filling material forms a loose, tubular structure within the said facing material.

2. A method of making a necktie or the like which consists of sewing together the four adjacent edges of a doubled-over piece of facing and a doubled-over piece of filling material, the said facing being doubled-over 95 so as to be inside out, and then turning the structure thus made inside out.

3. A necktie or the like comprising a piece of facing material sewed together along the median line of the rear thereof, the said 110 facing having within it a piece of filling material whose edges are connected to each

other and to the facing by the same stitches which connect the edges of the facing, substantially the entire remaining part of the said filling material being unsecured to the 5 said facing material, so that the said filling material forms a loose, tubular structure within the said facing material.

4. A necktie or the like comprising a doubled-over facing and a doubled-over piece of 10 filling material therein, the four adjacent

edges of the facing and the filling being connected to each other, substantially the entire remaining part of the said filling material being unsecured to the said facing material, so that the said filling material forms a loose, 15 tubular structure within the said facing material.

I testimony whereof I hereunto affix my signature.

THEODORE FRUCHTMAN.
